UNITED STATES PATENT OFFICE.

MAHLON E. FIRST, OF LAKEWOOD, OHIO, ASSIGNOR TO THE C. O. BARTLETT & SNOW COMPANY, OF CLEVELAND, OHIO, A CORPORATION OF OHIO.

MATERIAL-HANDLING MECHANISM.

Application filed October 23, 1922. Serial No. 596,333.

The present improvements relating, as indicated, to material handling mechanism have more particular regard to mechanism for loading, i. e. transferring, material into 5 railway cars, trucks or the like that may be brought successively to a loading station. Conversely said mechanism may be employed in the removal of material from such vehicles. The object of the invention is to provide a 10 machine for the general use stated that will be sufficiently flexible so that the material may be delivered at various elevations and at least in either of two opposite directions. Having regard to the particular use of the 15 machine referred to, i. e. for loading railway cars, and more especially box cars, the construction of the machine is such as to permit such loading to be carried on in the case of cars standing on tracks on either side of the 20 machine and, if desired, the latter may be adapted to handle material in connection with cars on either of two parallel tracks on each such side.

To the accomplishment of the foregoing 25 and related ends, the invention, then, consists of the means hereinafter fully described and particularly pointed out in the claims, the annexed drawings and the following description setting forth in detail certain mechanism 30 embodying the invention, such disclosed means constituting, however, but one of various mechanical forms in which the principle of the invention may be used.

In said annexed drawings:—

Fig. 1 is a side elevation of a machine embodying my present improvements, such machine being primarily designed for loading cars as aforesaid; Fig. 2 is a transverse section of such machine on a somewhat larger scale, 35 the plane of the section being indicated by the line 2—2, Figs. 1 and 3; Fig. 3 is a similar transverse section taken on the plane indicated by the line 3—3, Fig. 2; Fig. 4 is a transverse section on the plane indicated by the 40 lines 4—4, Figs. 1 and 3; and Fig. 5 is a view similar to Fig. 1 but showing a modification 45 of the machine.

It has not been deemed necessary for the 50 purpose in hand to illustrate the main supporting structure upon which the mechanism of present interest is mounted other than to indicate in Figs. 1 and 2 the beams 1 whereon are supported laterally spaced coaxial bearing blocks 2 from which the main frame of 55 the machine is oscillatorily suspended. Such

main frame, as best shown in Figs. 1 and 2, comprises two similar side members 3 which may be in the form of castings or built up of suitably reinforced plates and which are of irregular polygonal outline, as shown in such 60 Fig. 1. The upper end of each such side member terminates in an outwardly directed yoke 4 through which passes a pin 5 that serves to secure said member in the corresponding bearing block 2. Said side members are connected together by means of a plurality of 65 transverse bars 6 attached near their respective lower edges and forming an assembled structure on the order of a cradle, it being in this cradle that the various operative parts 70 of the machine are carried.

This cradle-like structure with the various parts carried thereby is angularly positioned about the axis defined by the pins 5 whereby such cradle is suspended from bearings 2 75 through the medium of two similar arcuate racks 10, located one adjacent the outer face of each side member 3, said racks being fixedly secured to the supporting structure 1 and being engaged by pinions 11 on a transverse shaft 12 journaled in said side members. The effect of rotating said shaft in one direction or the other will obviously be to rock the cradle about the common axis of pins 5 in a corresponding direction. For the purpose 85 of thus rotating said shaft, any suitable driving mechanism carried by the cradle will of course serve, but that shown in my preferred construction comprises an electric motor 13 disposed with its axis on a longitudinal median line of the machine. The motor is thus mounted near one end of the cradle and its spindle is directly connected with an aligned shaft 14, supported in suitable bearings, that extends towards the opposite end of such 90 cradle where it is connected through spur gearing 15 to drive two parallel shafts 16 and 17. The latter are adapted to be optionally thus driven from said shaft 14 through the medium of interposed clutches 18 and 19 and 95 are in turn connected with worm reduction gearing of standard design encased in housings 20 and 21, respectively. From the latter, transverse shafts 22 and 23, respectively, extend in opposite directions, being journaled 100 at their outer ends in suitable bearings provided in the adjacent side frames 3 of the cradle. One such shaft, viz., shaft 22, is connected to drive said shaft 12 through spur gearing 24, while the other shaft serves an- 110

other purpose, as will be presently described.

It will be understood that the motor 13 is of the reversible type and that suitable switches for controlling same may be located 5 remote from the machine along with suitable controlling devices for the clutches 18 and 19.

The conveying mechanism proper, in the illustrative form shown, comprises an endless belt 30 that passes around two large rollers or drums 31, respectively mounted in the opposite ends of an elongated frame 32 that is longitudinally adjustably supported in the aforesaid cradle. Said frame, as best shown 10 in Fig. 2, comprises side channel members 33 suitably joined together as by cross bars or plates 34 so as to form a rigid structure, the lower edges of said channel members being reinforced by angular rails 35 that are adapted 15 to contact with two pairs of flanged rollers 36 in the cradle, which thus serve as the direct means for movably supporting said frame as aforesaid. In order to hold the frame on said rollers 36, a third pair of rollers 20 37, conveniently mounted on the same pins 5 that form the oscillatory support for the cradle, are disposed so as to contact with the upper face of the frame on each side thereof. Said rollers 37, it will be noted 25 (see Fig. 1), are located approximately midway of the two pairs of rollers 36 and thus serve to maintain the conveyor frame in fixed angular relation to the cradle, irrespec- 30 tive of oscillation of the latter, and at the same time said conveyor frame is left free to move in a longitudinal direction between the several pairs of rollers.

The load of material carried by the conveyor belt 30 will of course rest on the upper 40 lap thereof and, accordingly, in order properly to support the same, a number of intermediate transversely disposed rollers 38 is provided on the upper side of said conveyor frame. The respective sides of such upper 45 lap of belt 30 are furthermore guarded by means of longitudinally extending plates 39 supported from channel members 33 through the medium of brackets 40. In order that the conveyor belt 30 may be maintained under 50 proper tension, a roller 41, similar to rollers 38, is mounted in the conveyor frame in position to contact with the lower lap of the belt, as shown in Fig. 1, such roller being adjustable transversely of the plane of the belt, as 55 will be readily understood.

For the purpose of longitudinally moving the conveyor frame in either direction as desired between the several pairs of rollers 36 and 37, suitable driving connections are provided 60 between the same and the shaft 23 hereinbefore referred to as being driven through clutch 19 and reduction gearing 21 from the same motor 13 that is utilized to oscillate the cradle, together with the mechanism thus carried thereby, about the com-

mon axis of pins 5. Such last mentioned driving connections include a pinion 46 on said shaft 23 that is connected to drive a spur gear 47 and thus the shaft 48 whereon the latter is fixed. Such shaft 48 is in turn provided with spaced spur pinions 49 that engage with rack teeth 50 formed on the under sides of the rails 35 whereby the conveyor frame is movably supported on the flanged wheels 36, as previously described. Rotation 70 of such shaft 48 in one direction or the other will accordingly serve to move said conveyor frame in the corresponding direction so as to cause the latter to project to the right beyond the cradle, as shown in full lines in 75 Fig. 1, or to the left without change in the angular position of the cradle, as shown in dotted outline in the same figure. Obviously any intermediate position may be given the conveyor frame and the angle of inclination 80 of the frame will of course be varied as the cradle is rocked about the axis whereon it is hung.

The conveyor belt 30 is driven from a separate motor 60 that is attached to the under side of the conveyor frame near one end thereof, the left end, as shown in Fig. 1. This motor is connected with the adjacent roller or drum 31 through the medium of a standard reduction gear 61 and a spur gear 62 that meshes in turn with a spur gear 63 on the shaft of said drum. As in the case of motor 13, said motor 60 may, if desired, be of reversible type so that the conveyor belt may be driven in either direction as desired, a suitable control for said motor being provided at a point remote from the machine or at some point thereon at all times accessible to the operator, as need not be described in detail.

Thus in the second dotted position shown in Fig. 1, said conveyor frame has its left end tilted upwardly and its right end downwardly so as to bring such right end, which is intended in the construction shown to be the discharge end of the machine, into position to deliver material received on the conveyor belt into a car body or other suitable receptacle. For the purpose of properly distributing material within such car body, a supplemental loading device, such as the Maniere loader 51, shown in dotted outline in Fig. 1, may be employed, and the material may be supplied to the conveyor belt from a discharge chute 52 located above the machine 110 or in any other suitable manner, neither such loader 51 nor such supply means 52 constituting any part of the present invention.

The operation of the machine as a whole will require but brief additional explanation 115 in view of the foregoing description of the several component parts and the operation thereof, respectively. The cradle which constitutes the main frame of the machine will be rocked about its axis to properly incline 120 125 130

the conveyor frame so as to discharge the material received on the conveyor belt at the desired elevation when such conveyor frame has been longitudinally extended or retracted to bring its discharge end into necessary proximity either of the vehicle to be loaded or of the intermediate loading device, such as the Maniere loader, whereby the material is to be finally distributed in such vehicle. It will be evident that by making the conveyor frame of sufficient length, the machine may be readily adapted thus to deliver material from a relatively fixed source of supply, such as the discharge chute 52, into freight cars standing on either of two parallel tracks. Furthermore, by changing the direction of movement of the conveyor belt, the machine is at once adapted for corresponding delivery into cars extending on either of two parallel tracks on the opposite side of the machine. The delivery end of the conveyor frame may not only be adjusted initially to any elevation, but may be raised as the loading operation proceeds and the car body or other receptacle is filled.

Finally, as shown in Fig. 5, the machine, instead of being supported on a stationary framework, may be mounted on a turntable, i. e., the supports for the bearings 2 from which the cradle is hung may be mounted on a platform 55 rotatable about a vertical axis either central with respect to the machine or otherwise as desired. In this way the radius of action for the machine will be correspondingly increased.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a suitable support, a frame oscillatorily mounted thereon, a second frame longitudinally reciprocable in said first frame, a conveyor carried by said second frame, and means in said first frame respectively adapted to oscillate same relatively to said support and to reciprocate said second frame, said oscillating means including an arcuate rack on said support and a motor-driven pinion on said first frame in engagement with said rack.

2. In mechanism of the character de-

scribed, the combination of a suitable support, a frame oscillatorily mounted thereon, a second frame longitudinally reciprocable in said first frame, a conveyor carried by said second frame, and means in said first frame respectively adapted to oscillate same relatively to said support and to reciprocate said second frame, said reciprocating means including a straight rack on said second frame and a motor-driven pinion on said first frame in engagement with said rack.

3. In mechanism of the character described, the combination of a suitable support, a frame oscillatorily mounted thereon, a second frame longitudinally reciprocable in said first frame, a conveyor carried by said second frame, an arcuate rack on said support, a straight rack on said second frame, pinions in said first frame respectively meshing with said racks, and a motor on said first frame connected to drive said pinions as desired.

4. In mechanism of the character described, the combination of a suitable support, a cradle-like frame oscillatorily mounted thereon, a second frame longitudinally reciprocable in said frame, a conveyor carried by said second frame, and means in common for oscillating the said cradle-like frame and reciprocating said second frame, said means including a segmental rack fixed to said support and a shaft in said cradle-like frame and carrying a gear in mesh with said rack.

5. In mechanism of the character described, the combination of two co-axial spaced bearings, a depending cradle-like frame oscillatorily supported from said bearings between the same, suitable guides in said frame, a second frame held in said guides so as to be longitudinally reciprocable transversely of the axis of said first frame, a conveyor carried by said second frame, a rack and pinion for oscillating said first frame, another rack and pinion for reciprocating said second frame, a motor mounted in said first frame with its spindle disposed transversely of the axis of oscillation of said frame, shafts lying parallel with said motor spindle and adapted to be optionally intergeared therewith, and worm-reduction gearing connecting said last mentioned shafts with said pinions, respectively.

Signed by me this 16th day of October, 1922.

MAHLON E. FIRST.
